UNITED STATES PATENT OFFICE.

ALFRED HEALD, OF PHILADELPHIA, PA., ASSIGNOR TO HUGH McCALLUM, ORLANDO CREASE, AND ANDREW J. SLOAN, OF SAME PLACE.

DESIGN FOR CARPET-PATTERN.

Specification forming part of Design No. **11,294**, dated July 15, 1879; application filed June 16, 1879.
[Term of patent 3½ years.]

To all whom it may concern:

Be it known that I, ALFRED HEALD, of Philadelphia, Pennsylvania, have produced or invented a new and original Design for a Carpet-Pattern, of which the following is a specification.

My design for a carpet-pattern is shown in the accompanying photographic illustration.

The design is of a composite character, the central figure, *a*, being of a square outline, one corner of the figure overlapping an octagonal figure, *b*, and the opposite corner overlapping a figure, *d*, in the shape of a Greek cross. One of the other corners of the figure *a* is overlapped by an oblong figure, *e*, and the remaining corner is overlapped by an irregularly-shaped figure, *f*.

The remainder of the design comprises the

oval figure *g*, square figures *h* and *k*, right-angled figures *i*, *m*, and *n*, and bands or stripes *s*, *t*, *w*, *x*, and *y*.

The ornamentation of the different figures, bands, and stripes is too fully shown to need description.

Irrespective of the colors employed, I claim—

The design for a carpet-pattern, consisting of the arrangement of figures, bands, and stripes, substantially as described, and as shown in and by the accompanying photographic illustration.

In testimony whereof I have signed my name to this specification in the presence of two subscribing witnesses.

Witnesses: ALFRED HEALD,
